UNITED STATES PATENT OFFICE.

CHRISTIAN H. MARTIN, OF AKRON, OHIO.

DESIGN FOR A PIANO-BENCH.

45,912.

Specification for Design.

Patented June 9, 1914.

Application filed April 17, 1914. Serial No. 832,646. Term of patent 7 years.

To all whom it may concern:

Be it known that I, CHRISTIAN H. MARTIN, a citizen of the United States, residing at Akron, in the county of Summit and State of Ohio, have invented a new, original, and ornamental Design for Piano-Benches, of which the following is a specification, reference being had to the accompanying drawing, forming part thereof.

Figure 1 is a perspective view looking at the front of a piano bench embodying this design; and Fig. 2 is a similar view, looking at the rear thereof.

I claim:

The ornamental design for a piano bench, as shown.

CHRISTIAN H. MARTIN.

Witnesses:

J. A. ARBOGAST,
ALLEN MARTIN.
